UNITED STATES PATENT OFFICE

CHARLES SZYPER AND EMERY MIHALEK, OF CHICAGO, ILLINOIS, ASSIGNEES TO O. D. JENNINGS & COMPANY, OF CHICAGO, ILLINOIS, A CORPORATION OF ILLINOIS

COIN CHUTE MECHANISM

Application filed April 1, 1931. Serial No. 526,830.

This invention relates to a coin controlled apparatus such as a vending machine.

Considerable trouble has been experienced in the past by proprietors or users of coin controlled vending machines due to the practice of using spurious coins. Many devices have been arranged to detect false coins and to prevent the operation of the machine upon the use of such a coin. These devices, however, do not give any indication of the presence of such coin in the machine in order to prevent subsequent futile attempts to use the machine, nor do they give an indication of the presence of a spurious coin to enable the proprietor of the machine to apprehend the user during the playing thereof or after the coin has been played.

Difficulties have also been encountered where a coin chute of any substantial length has been employed due to crowding and overlapping of the coins therein or due to failure of the coins to pass along the chute in the proper manner.

It is the purpose of this invention, therefore, to provide a coin controlled mechanism suitable for use in a vending machine, for example, in which a plurality of coins are always exposed to view and in which a selected coin in the chute will control the operation of the machine and to provide means for positively conveying the coins along the coin chute in such a manner that each coin is positively fed and prevented from overlapping or jamming with adjacent coins.

In accordance with this invention a relatively long chute having a transparent wall is employed which will expose to view a plurality of coins in the chute. Means are provided for positively feeding the coins throughout the entire length of the chute and for supporting or spacing the coins in such a manner as to prevent overlapping thereof.

Other novel features of this invention and their resultant advantages will be apparent from the following description given in connection with the illustrative forms of this invention shown in the drawings, in which:

Fig. 1 is an end elevation of the coin con-

trol mechanism portion of a vending machine;

Fig. 2 is a rear elevation of the coin control mechanism;

Fig. 3 is a front elevation of the coin control mechanism shown in Fig. 2;

Fig. 4 is a fragmentary section taken on line 4—4 of Fig. 2;

Fig. 5 is a fragmentary section taken on line 5—5 of Fig. 2;

Fig. 6 is a detail of a single link of the conveyor chain;

Fig. 7 is a perspective view of the locking lever;

Fig. 8 is a front elevation of a fragment of the coin chute illustrating a slightly modified form of conveyor chain;

Fig. 9 is a section on line 9—9 of Fig. 8; and

Fig. 10 is a rear elevation of a modified form of coin control mechanism.

Referring particularly to the form of this invention illustrated in Figs. 1 to 7, inclusive, it will be seen that the coin control mechanism is supported principally upon

one end plate 1 of the vending machine. The coin chute is formed by a pair of plates 2 and 3 secured to the end frame, the latter plate being the front plate is preferably formed of some transparent material such as glass. The plates are held in spaced relation the thickness of a coin 5 by a pair of spacing bars 4 and 6 extending along the marginal edges of the two plates 2 and 3, and spaced apart sufficiently to permit passage of a coin 5 therebetween. Plates 2 and 3 and spacers 4 and 6 are clamped together by any suitable clamping means 7. The space thus provided between back plate 2, front plate 3 and spacers 4 and 6 provides a relatively long L-shaped coin chute. Near the forward end of the plates a mouthpiece 8 is provided which communicates with one end of the coin chute and guides the incoming coins thereinto. The chute is arranged to discharge the coins into a receptacle 9.

In order to positively feed and space coins within the chute to prevent overlapping thereof, a conveyor chain 11 is provided which travels over a pair of sprockets 12

and 13 journaled upon short shafts 14 and 16 respectively, the latter being secured to the inner plate 2. Selected links of the conveyor chain are provided with fingers 17 that extend through slots formed in the inner plate 2 and project into the coin chute in the path of the coins. These fingers are arranged to engage the coins 5 approximately in the center thereof and are sufficient in number and so spaced as to provide successive pockets for the coins. The fingers thus positively engage each coin to move it along the chute and to positively space each coin and prevent its crowding the adjacent coin.

15 In order to drive the conveyor chain a lever 18 is pivoted to the end frame 1 at 19 and is provided with an operating handle 20. Lever 18 also serves to actuate any desired vending mechanism (not shown) 20 through a connecting rod 21. The lever 18 is operatively connected by a link 22 to a vertical pull rod 23, the latter being held against lateral movement by a tongue 24 projecting outwardly from plate 1 and engaging in a slot 26 in rod 23. The upper end of rod 23 is pivotally connected to one end 27 of a lever 28, the other end of which is journaled upon shaft 14. Intermediate its ends and adjacent end 27, lever 28 is provided with a pivoted pusher dog 29 having a reduced projecting finger 31 providing shoulder 32 where it joins the dog. Finger 31 and its shoulder 32 are arranged to engage pins 33 projecting laterally from a disc 34 secured to the hub 36 of the sprocket 14 for rotation therewith. Dog 29 is maintained in engagement with pins 33 by spring 37. A friction device 38 is arranged to contact disc 34 to retain the disc and conveyor chain stationary while the dog 29 is retracted to assume a new stroking position. The friction device will also serve to keep the conveyor chain from being jarred around during shipments or by attempts to abuse the machine.

45 From the foregoing it will be observed that as handle 20 is pushed downwardly to rotate lever 18 about its pivot 19, pull rod 23 will pull lever 28 downwardly and cause shoulder 32 of dog 29 to engage a pin 33 and rotate disc 34 about its shaft and move the conveyor chain to carry a coin one step along the chute. The pins and movements of the levers and rods previously mentioned are so designed as to impart a movement to the conveyor chain equal to substantially the diameter of one coin upon one movement of handle 20.

In order to lock the coin control mechanism against operation unless there is a coin in the chute at some predetermined position, a locking rod 41 is pivoted intermediate its ends at 42 to a bracket 43 secured to rear plate 2. One end of the rod is provided with an inwardly projecting finger 44 which projects into the coin chute

to engage a coin therein if present. The other end of the lever is provided with a pin-like projection 46 which extends through the end frame 1 and into an elongated slot 47 formed in pull rod 23. When the finger 44 is in engagement with a coin in the chute finger 46 is maintained in the straight portion of slot 47. Whenever, however, a coin is not present at the entrance to the chute and in engagement with finger 44, locking lever 41 will be swung about its pivot by spring 48 (Fig. 5) to cause pin 46 to enter a recess 49 (Fig. 1) formed in slot 47 and prevent downward movement of pull rod 23.

It is obvious that the lever 41 may be made of any desired length in order to bring the finger portion 44 into any desired position along the chute. In the illustrated form it is extended so as to contact the coin nearest the entrance to the chute.

Referring to the form of this invention illustrated in Figs. 8 and 9, it will be observed that the structure is similar to that described in connection with Figs. 1 to 7 with the exception that the fingers 17a formed upon links 11 of the conveyor chain are arranged to engage the coins below the center thereof in order to permit the coins to be closer together in the chute and thereby give greater capacity to the chute and expose more coins to view.

In the modification illustrated in Fig. 10, an even longer coin chute is provided by doubling the chute upon itself, i. e. forming the chute in two connected rows, one superimposed upon the other and utilizing both stretches of the conveyor chain to move the coins continuously through the chute.

It will be observed that in this form the chute is of U-formation and is provided with a mouthpiece 51 which conducts the coins into the leading end of the coin chute 52 formed, as previously mentioned, between two spaced plates. One end, the upper stretch, of the chute is curved as at 53 and the chute continues below a partition 54, discharging as at 55 into a suitable coin receptacle (not shown). In this illustrated form the mouthpiece 51 is adjacent the end plate 56 and operating pull rod 57. Consequently the locking rod 58 is considerably shorter but functions similarly to that described in connection with rod 41. The conveyor chain is provided with projecting fingers 58, as previously described, which feed the coins through the chute in spaced relation. The actuating mechanism for the conveyor chain comprises a curved lever 59 having a feed dog 61 pivoted thereto. The operation of this form of the invention is identical to that described in connection with the form illustrated in Figs. 1 to 7 and will not be repeated.

It is obvious from the foregoing description that there has been provided a coin con-

trol mechanism for a vending machine in which a plurality of coins are visible at all times and in which the coins are positively fed through the chute without any possibility of overlapping or jamming and in which the entire coin control mechanism is positively locked against operation unless a coin is inserted in the chute at a prescribed point. The entire mechanism may be economically 5 manufactured and is not unsightly to the eye.

It is obvious that minor changes may be made in the details of the invention without departing from the scope of this invention as defined in the claims appended here- 10 to.

We claim:

1. In a coin controlled apparatus, a coin chute of sufficient length to accommodate a 20 plurality of coins in succession prior to reaching discharging position, and a conveyor chain, said chain having means thereon for engaging each of the coins in said chute for positively simultaneously feeding 25 said coins through said chute, said means being arranged to permit the coins to abut but prevent overlapping.

2. In a coin controlled apparatus, a coin chute of sufficient length to accommodate a 30 plurality of coins in succession prior to reaching discharging position, a conveyor chain having projecting fingers extending from certain links thereof for positively simultaneously feeding each of the coins 35 through said chute, means for driving said chain continuously in one direction, means for locking said latter means against movement and means for releasing said locking means upon the presence of a coin at a pre- 40 determined point in said chute.

3. In a coin controlled apparatus, a coin chute of sufficient length to accommodate a plurality of coins in spaced succession prior to reaching discharging position, means for 45 advancing coins through said chute comprising a conveyor chain extending through a substantial portion of said chute and having coin spacing and engaging means thereon, means for moving said chain continuously in one direction, and means for preventing movement of the chain in the opposite direction.

4. In a coin controlled apparatus, a coin chute of sufficient length to accommodate a 55 plurality of coins in spaced succession prior to reaching discharging position, means for positively simultaneously feeding all of the coins in the entire chute, means for arresting the operation of said feeding means, and 60 means adjacent the entering end of said chute for releasing said arresting means upon the presence of a coin at the entrance of said chute.

5. In a coin controlled apparatus, a con- 65 tinuous coin chute arranged to support a

plurality of coins in spaced non-overlapping relation, said chute comprising two parallel connected and closely adjacent rows, and a conveyor chain extending throughout substantially the entire length of said chute 70 and having means thereon for positively engaging each coin in the chute and simultaneously feeding all of said coins through said chute.

In witness of the foregoing we affix our 75 signatures.

CHARLES SZYPER.
EMERY MIHALEK.
